CLAIM

The ornamental design for a keyboard dock for an electronic device, as shown and described.

DESCRIPTION

FIG. 1 is a front, top, right side axonometric view of a keyboard dock for an electronic device showing my new design:

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a rear, bottom, left side axonometric view thereof; and,

FIG. 9 is a front, top, right side axonometric view of the keyboard dock for an electronic device of FIG. 1, shown in a state of use with additional environmental subject matter. The broken lines in FIG. 9 that show the additional tablet computer depict environmental subject matter only and form no part of the claimed design. All other broken lines seen in the drawings depict portions of the keyboard dock for an electronic device that form no part of the claimed design.
